(57) **CLAIM**

The ornamental design for a wall mounted bar, as shown and described.

DESCRIPTION

FIG. 1 is a perspective view of a wall mounted bar showing our new design;

FIG. 2 is a front elevational view thereof; and,

FIG. 3 is a top plan view thereof, the bottom side being a mirror image of the side shown.

The bar shown broken-away in the views is understood to represent indeterminate length.
